UNITED STATES PATENT OFFICE.

JOHN HERZICK, OF ST. CLAIRSVILLE, OHIO.

NONREFILLABLE BOTTLE.

Application filed November 16, 1928. Serial No. 319,784.

This invention relates to bottles and more particularly to bottles of the non-refillable type.

There is a constant demand by manufacturers of standard liquid products for receptacles to prevent the adulteration of their products, or to refill the receptacle with a spurious liquid which may be sold in the well known bottle of the manufacturer and thus deceive the public with the resulting damage to the trade name of the manufacturer.

It is therefore an object of this invention to provide a bottle which may not be refilled, thus preventing the passing off of substitutes under a standard trade name.

A further object of the invention is the provision of a non-refillable bottle which is simple in structure and manufacture and which may have an outward appearance similar to the ordinary bottle.

These and other objects are attained by the novel construction, combination and arrangement of parts hereinafter described and shown in the accompanying drawing constituting a material part of this disclosure and in which:—

Figure 1 is a sectional view taken on line 1—1 of Figure 3.

Figure 2 is a sectional view taken on line 2—2 of Figure 3.

Figure 3 is a cross-sectional view taken on line 3—3 of Figure 1.

Referring to the drawing, a bottle having a body 4 is provided with a neck 5 with a constricted portion 6 where the neck enters the body 4. The mouth of the neck has an external bead 7 which receives the flange 8 of a cap 9, the latter being effectively sealed over the mouth of the neck by a washer 10 of cork, rubber or similar material.

Through an aperture 11 in the cap and washer, passes a rod 12 having a handle 13 at its free end which extends beyond the mouth of the neck 5. A ball 14 is attached to the other end of the rod 12, and is of such a diameter as to prohibit its passage through the constricted portion 6 into the body of the bottle.

At an intermediate portion of the neck 5, between the ball 14 and the mouth of the neck is positioned a disc 15 of rubber or similar materials, this disc being provided with an elongated slot 16 through which the rod 12 passes. The disc is also provided with a plu-

rality of apertures 17 which enable the passage of the liquid from the bottle to the mouth. To prevent the removal of the disc 15 and the ball 14, the interior walls of the neck are inclined at 18 at the mouth, to provide a restricted opening of less diameter than the disc or the ball.

In operation, it will be seen that liquid may be poured from the bottle and the disc 15 will prevent the ball from closing the mouth at the restricted portion 18, the liquid passing through the apertures 17 in the disc. It should be noted that the rod 12 is detached from the ball 14 when the bottle is in commercial use and imperforated caps 9 and 10 supplied, and should an attempt be made to refill the bottle, the ball 14 will fall into the restricted portion 6 of the neck and prevent any liquid from going into the body of the bottle.

Now, when the owner of the bottle, or the manufacturer of the standard liquid product desires to use the bottle again or to fill it in the first instance, the rod 12 is attached to the ball 14, which is pulled up and held against the disc 15, and when the ball is in such position the bottle may be filled.

From the above description it will be seen that there has been provided a bottle which may not readily be refilled by unauthorized persons, yet at the same time providing means for filling the bottle by authorized persons.

The foregoing disclosure is to be regarded as descriptive and illustrative only, and not as restrictive or limitative of the invention, of which, obviously an embodiment may be constructed including many modifications without departing from the general scope herein indicated and denoted in the appended claims.

Having thus described my invention, what I claim as new and desire to secure by Letters Patent is:

1. A non-refillable bottle, comprising a body, a neck having a constricted portion where it joins the body, an apertured disc positioned in the neck midway of its length a ball movable in the neck between the disc and the constricted portion, a rod detachable connected with the ball and slidable through a slot in the disc, and a cap to cover the mouth of the neck, the diameter of the mouth being less than the diameter of the disc.

2. A non-refillable bottle, comprising a body, a neck having a constricted portion

where it joins the body, an apertured disc positioned in the neck midways of its length, a ball movable in the neck between the disc and the constricted portion, the diameter of the ball being greater than the diameter of the constricted portion, a rod detachable connected with the ball and slidale through a slot in the disc, an external bead on the neck of its mouth, and a cap having flanges engaging the bead, the diameter of the mouth being less than the diameter of the disc. In witness whereof I have affixed my signature.

JOHN HERZICK.
